(57) **CLAIM**

We claim the ornamental design for a camera matte box, substantially as shown and described.

DESCRIPTION

FIG. 1 is a perspective view of a camera matte box in accordance with the present design.

FIG. 2 is a right side view of the camera matte box of FIG. 1.

FIG. 3 is a left side view of the camera matte box of FIG. 1.

FIG. 4 is a rear view of the camera matte box of FIG. 1.

FIG. 5 is a front view of the camera matte box of FIG. 1.

FIG. 6 is a bottom plan view of the camera matte box of FIG. 1; and,

FIG. 7 is a top plan view of the camera matte box of FIG. 1.

The broken lines depict portions of the camera matte box in which the design is embodied and form no part of the claimed design.

1 Claim, 7 Drawing Sheets
